SHAVING APPARATUS

William T. Weidenman, Spring Valley, N. Y., assignor to Telephonics Corporation, New York, N. Y., a corporation of New York

Application January 26, 1938, Serial No. 186,914

6 Claims. (Cl. 30—43)

This invention relates to a shaving device of the power driven type and has particular reference to the so-called dry shaving devices which cut the hair to the level or surface of the skin without the necessity for employing lather or other preparations to facilitate the shaving operation.

Dry shaving devices operate in the fashion of hair clippers, that is, they embody a stationary shear plate provided with an aperture or slot, one edge of which acts as a blade between which and the cooperating edge of a moving inner cutter, either reciprocating or rotary, the hair is caught and sheared off, the cutter wiping the under surface of the shear plate in its movement.

The commercial dry shavers of this class generally take two forms, characterized by either a flat or by a rounded or cylindrical outer shear plate, and each form has certain operating advantages not found in the other. For example, the flat shear plate enables end-shearing across its entire width, and affords the principal advantage of protection against abrasion of the skin by the inner cutter teeth because the shear plate blades intervene. However, because the cutting is performed through the flat shear plate it must be made so extremely thin to provide a close shave that it requires support against flexing during shaving. Also because the shear plate is flat, it cannot reach the hairs in the crevices without the use of hair lifting shoes or a comb for guiding the hair in an erect position into the cutting zone of the inner cutter.

The round or cylindrical outer shear plate tends to stretch the skin because of its curvature and thus erects the hair for side shearing by exposed inner and outer shearing teeth cooperating in the manner of a conventional hair clipper, so that the outer shear plate teeth perform the hair-lifting function and special shoes or combs for that purpose become unnecessary. However, it is necessary to provide a guard to protect the skin from abrasion by the exposed shearing teeth, and where they are not so exposed, hair-lifting shoes must be employed.

I have found that in both flat and round shear plate forms of dry shaving devices, all or most of the hair shearing is effected at the line of juncture of the leading edges of outer shear plate blades and the cutter teeth and that the amount of end cutting across the entire width of the flat shear plate is negligible, so that it is necessary to provide only a very narrow or substantially single line cutting zone.

In accordance with the present invention, a dry-shaving device of the reciprocating inner cutter type is provided, which has a narrow cutting zone and combines the advantages of the round outer shear plate of skin-stretching and of dispensing with hair-lifting shoes or comb, with the advantage of the flat shear plate of preventing abrasion of the skin by the inner cutter by performing the shearing operation through an intervening web.

In its preferred embodiment, the dry-shaving device of this invention includes an inverted, channel-shaped outer shear plate having an arched skin-engaging surface with a row of transverse slots along each lateral side extending part way across the skin-contacting surface and part way down the side walls of the channel shear plate. The two rows of blades formed by these slots are accordingly separated by a non-cutting strip of substantial width extending longitudinally of the center of the skin-engaging surface and this strip is rendered more rigid by a rib extending longitudinally of the under surface of the shear plate and merging at its ends into transverse shoulders across the ends of the shear plate.

The blades on the shear plate are accordingly angle-shaped and are rigidly supported at their opposite ends by the non-cutting center strip and the side walls of the channel shear plate, thus enabling the blades to be reduced to extreme thinness at their apices, i. e. along the opposite lateral sides of the skin-engaging surface, without impairing their rigidity and without rendering them subject to flexing under abnormal shaving pressures.

Positioned within the inverted channel-shaped shear plate is a channel-shaped inner cutter, the upper longitudinal edges of the arms of which are serrated transversely to provide teeth cooperating with the blades of the shear plate at their thinnest points, so that, as the inner cutter is reciprocated by suitable power driven means, the hair shearing is effected only in a narrow zone along each opposite side of the skin-contacting surface of the shear plate, so that line-cutting results.

It will be seen that, inasmuch as the shearing zone is confined to the leading side of the skin-contacting surface of the shear plate as the latter is moved over the skin, the hairs are immediately attacked by the inner cutter, so that hair-guiding slots and hair-lifting shoes or comb become unnecessary, and this feature plus the skin-stretching feature of the arched skin-

engaging surface, provide the principal advantages of the usual round head shaving devices, whereas the protection against skin abrasion afforded by enclosure of the inner cutter the shear plate teeth provides the principal advantage of the usual flat head shaving device.

The device may have one cutting side or two, which are effective when the device is moved in opposite directions and where two cutting sides are employed, the slots forming the blades are displaced laterally on the opposite sides, so that a slot on one side is opposite a blade on the other side, whereby the hairs not cut by the leading side, by reason of being covered by a blade, pass into the opposite slot and thus more hairs are cut during a straight line movement back and forth over the skin. Other advantages of the dry-shaving device of the present invention will become apparent upon examination of the accompanying drawing, in which:

Figure 1 is an enlarged longitudinal section through the operative portion of the shaving device of this invention, as seen along the line 1—1 of Fig. 2;

Fig. 2 is an elevation of the operative portion of the shaving device, shown in partial longitudinal section and with other portions of the shaving head broken away to illustrate its construction;

Fig. 3 is an enlarged fragmentary plan view 30 of the skin-contacting surface thereof;

Fig. 4 is an enlarged fragmentary elevation thereof; and

Fig. 5 is an enlarged fragmentary elevation of the inner cutter, partially broken away.

Referring to Figs. 1 and 2 of the drawing, numeral 10 designates a handle, preferably of composition material containing electro-motive means, such as a motor or vibrator for oscillating the lever 11 pivoted at 12 on a suitable frame, such as the bar 13 anchored at its ends in the handle 10. The lever projects through an aperture 14 in the base of the cutter head 15 and engages the channel-shaped inner cutter 16 for reciprocating it rapidly within the hollow shear plate body 17. The cutter head 15 is mounted in a slot at the upper end of the handle 10 and is locked in fixed position therein by a set screw 18, or the like.

The cutter head 15 includes the hollow shear plate body 17 and the inner cutter 16. The shear plate body 17 comprises an inverted channel having a longitudinally-arched or cylindrical skin-contacting surface 20 and integral side walls 21 which converge downwardly as shown in Fig. 1 so that the cutter head 15 is generally keystone-shaped in cross-section. The lower ends of the side walls 21 are suitably secured to a spacer 22 providing the center aperture 14 for the oscillating lever 11.

The opposite lateral sides of the shear plate body 17 are provided with spaced slots 23, which are of sufficient width to allow the free passage of hairs but too narrow to admit the skin. The slots 23 extend only partially across the skin-contacting surface and part way down the side walls 21, leaving an imperforate strip 24 extending longitudinally of the skin-contacting surface 20, this strip 24 constituting a non-cutting area. The width of the strip 24 is preferably about half the overall width of the skin-contacting surface 20.

The slots 23 accordingly form two opposite rows of blades 25 extending along both lateral sides of the skin-contacting surface 20. Prefer-

ably, the slots on opposite sides are staggered or displaced laterally, so that a blade 25 on one side lies directly opposite a slot 23 on the other side, as is illustrated in Fig. 3.

5 The slots 23 may be formed by a saw-cutting operation across each opposite edge of the shear plate body 17, thus providing the blades 25 with a rectangular cross-section. The relatively sharp outer corners of the blades 25 are preferably rounded off, as indicated at 26, to prevent abrasion of the skin during the shaving operation. The blades 25 are angle-shaped in transverse cross-section, as illustrated in Fig. 1, and are rigidly supported at their opposite ends by 10 the non-cutting center strip 24 and the side walls 21 of the shear plate body 15 and accordingly are inherently rigid. The center strip 24 is rendered especially rigid by an interior rib 27 extending coincidentally therewith longitudinally from end-to-end and merging at its opposite ends into the rigid transverse shoulders 28 at the ends of the shear plate body 15. By reason of this rigid construction of the blades 25, they may be reduced to a thinness of a few thousandths of 15 an inch at the longitudinal shearing line or zone 29 without impairing their rigidity, so that they do not flex even under abnormal shaving pressures and consequently require no additional support.

It will be observed that the blades 25 rapidly increase in thickness to either side of the thin zone 29, due to the arch in the cylindrical skin-contacting surface 20 on one side and the thickness of the side walls 21 on the other side. This 20 thin zone 29 may be obtained by broaching or otherwise cutting out the metal after the outer shear plate body 17 is shaped and slotted, thus providing sharp cutting edges for the inner walls of the blades 25.

35 The longitudinal edges of the upstanding arms 30 and the channel-shaped inner cutter 16 are provided with spaced transverse slots 31 forming the cutting teeth 32, the teeth on the opposite arms 30 being in transverse alignment with each other so that when a tooth 32 lies under a blade 25 on one side of the shear plate body 17, the corresponding opposite tooth 32 lies under a slot 23 on the opposite side of the shear plate body 17. The inner cutter teeth 32 are spaced from center to center the same distance as the blades 25 and are preferably slightly narrower than the latter, making the inner cutter slots 31 slightly wider than the slots 23 of the shear plate body. Thus the inner cutter teeth 32 register with the blades 25.

40 The inner cutter teeth 32 are cut square or true at their outer corners 32', as by saw-cutting or precision milling of the slots 31, so that when these outer corners 32' engage in the zone 29 of the shear plate body 17 the desired narrow or line cutting zone at 29 is achieved. Preferably, the inner cutter 16 is made of relatively thin resilient material with its arms 30 spread at a slightly greater divergence than the co-operating side walls 21 of the shear plate body 17, so that when the inner cutter 16 is inserted within the shear plate body 17, its outer upper edges are urged into intimate frictional engagement with the upper inner surfaces of the shear plate body side walls 21.

45 Also, the inner cutter 16 is urged resiliently outwardly with its teeth in intimate frictional engagement with the under surfaces of the blades 25 by plungers 33 slidably mounted in the handle 10 and bar 13 and extending through

the spacer 22 with their rounded upper ends in engagement with the lower surface of the inner cutter 16. A spring 34 extending between bar 13 and a shoulder 35 urges each plunger 33 upwardly or outwardly. The outer ends of the inner cutter base are provided with inclined grooves 36 to facilitate insertion of the inner cutter 16 without obstruction by the plungers 33.

In operation of the shaving device of this invention, the power means, such as the motor within handle 10, is placed in operation, causing lever 11 to oscillate about its pivot 12 and rapidly reciprocate inner cutter 16, so that its teeth 32 cooperate with the edges of the blades 25 of the shear plate body 17, alternately covering and uncovering slots 23. As the skin-contacting surface 20 is moved back and forth over the skin in the direction of the slots 23, the arched or outwardly-curved cylindrical surface 20 thereof stretches the skin, so that the hairs enter the slots 23 in the leading edge in an erect position to be immediately severed at the narrow or line cutting zone 29. Thus, no hair-lifting shoes or comb are needed and the skin abrasion frequently accompanying their use is avoided. The slight convergence of the side walls 21 reduces deflection out of the slots 23 of the inclined hairs by the blades 25 and the rounded ends of the latter aid this action as well as preventing abrasion of the skin. Also, the blades 25 intervene between the inner cutter teeth 32 and the skin so that abrasion by the inner cutter is prevented.

Because of the thinness of the shear plate body 17 along the shearing zone 29, a close shave is provided, the skin also being pressed slightly into the slots 23, so that the hairs are sheared at or below the normal skin level. Only light shaving pressure is necessary to obtain a close shave, but even if abnormal pressure is exercised, the blades 25 cannot flex because of their inherently rigid structure, so that no support for them against flexure is required.

Because of the staggered relation of the blades 25 on opposite sides of the shear plate body, those hairs which were not severed in one movement of the device in a right line over the skin by reason of being covered by the blades 25, are sheared by the opposite side of the device when it is moved in the same line in the opposite direction, because the hairs can enter slots 23 opposite those blades 25 that formerly covered the hairs, so that fewer passes over the skin are required to cut all the hairs. Although a two-sided shaving device is illustrated, a one-sided device may be provided by using half of the structure described.

It will be seen that a very efficient and simple dry shaving device is provided by this invention, having the enumerated advantages of those in current use while providing additional features contributing to more effective and rapid shaving. While the foregoing description and accompanying drawing are illustrative of a preferred embodiment of the invention, it is to be understood that the invention is not limited thereby, but is susceptible of changes in form and detail within the scope of the appended claims.

I claim:

1. In a shaving device, the combination of a substantially rectangular skin-contacting plate having transverse slots forming blades along the opposite longitudinal sides of said plate separated by an imperforate center portion, walls depending from the said opposite sides of said

plate and forming therewith a hollow body, a substantially channel-shaped movable cutter within said body having teeth along the edges of its upwardly-extending arms for cooperation with said blades, the said arms of said cutter being resiliently urged apart for intimate frictional engagement with the inner surfaces of said side walls, and means for reciprocating said cutter to shear hairs projected between said blades.

5 2. In a shaving device, the combination of an elongated skin-contacting plate having a convex outer surface and tapering in thickness from its longitudinal center line to its opposite longitudinal sides, said sides being slotted transversely to provide two rows of opposite blades separated by an imperforate longitudinal center strip, integral walls converging downwardly from the said opposite longitudinal sides of said plate, a movable cutter within said body having upwardly extending and outwardly diverging arms, said arms having teeth along their upper edges for cooperation with said blades, the said arms of said cutter being resiliently urged apart for intimate frictional engagement with the inner surfaces of said side walls, and means for reciprocating said cutter to shear hairs projected between said blades.

10 3. In a shaving device, the combination of a shaving head having a longitudinally extending 30 rib, sets of blades of substantially triangular shape in vertical section extending laterally from the rib in opposite directions, depending side walls integral with the outer ends of said blades and converging downwardly to form with the blades and rib a hollow body, a cutter member in said body, said cutter member comprising a pair of upwardly diverging arms resiliently urged outwardly at a greater angle than the angle of the side walls, teeth on the upper edges of the arms bearing against the inner surfaces of said triangular blades and the inner surfaces of said side walls adjacent to said blades, and means for reciprocating said cutter member.

15 4. In a shaving device, the combination of a substantially rectangular skin-contacting plate reduced to extreme thinness along its opposite longitudinal sides, said opposite sides being slotted transversely to provide blades, a reinforcing rib extending longitudinally of said skin-contacting plate between said blades, substantially flat walls depending from said opposite sides of said skin-contacting plate and forming therewith a hollow body, a channel-shaped movable cutter within said body having teeth along its upper longitudinal edges cooperating with said blades, means resiliently urging the teeth against the inner surfaces of said blades and outwardly against said walls adjacent the said blades, and means for reciprocating said cutter to shear hairs projected from said blades.

20 5. In a shaving device, the combination of an elongated skin-contacting plate reduced to extreme thinness along its opposite longitudinal sides and having a thickened reinforcing portion adjacent its center, said opposite sides being slotted transversely to provide blades, integral substantially flat extensions of said blades projecting downwardly from the thin sides of said skin-contacting plate and forming therewith a hollow body having inner and outer corner edges at the thinnest portions of said blades, a movable cutter within said body having a base spaced from said skin-contacting plate, side walls projecting upwardly from said base and notches

in the upper edges of said side walls forming teeth for cooperation with said blades, means for retaining said teeth in the said inner corner edges of said hollow body and in engagement with the thin portions of said blades, and means for reciprocating said cutter to shear hairs projected between said blades.

6. In a shaving device, the combination of an elongated skin-contacting plate having a convex outer surface and tapering in thickness from its longitudinal center line to its opposite longitudinal side, said opposite sides being slotted transversely to provide two rows of blades sepa-

rated by a thickened longitudinal center strip, integral walls converging downwardly from the said opposite longitudinal sides of said plate forming therewith a hollow, a movable cutter within said body having a base spaced from the said skin-contacting plate, side walls projecting upwardly from said base and notches in the upper edges of said side walls forming teeth for cooperation with said blades, and means for reciprocating said cutter to shear hairs projected between said blades.

WILLIAM T. WEIDENMAN.
